KARL ARNSTEIN, OF FRIEDRICHSHAFEN, GERMANY, ASSIGNOR TO LUFTSCHIFFBAU ZEPPELIN GESELLSCHAFT MIT BESCHRÄNKTER HAFTUNG, OF FRIEDRICHSHAFEN, BODENSEE, GERMANY.

RIGID AIRSHIP.

Application filed October 2, 1924, Serial No. 741,240, and in Germany October 13, 1923.

My invention relates to the hulls of rigid airships which are made up of longitudinal and cross members, particularly to the construction of the cross members which are called rings and generally have a polygonal shape. The sides of the polygon consist of girders, and such girders are braced by internal wire bracing. All this construction is situated in one plane and this plane is 10 rectangular to the ship's longitudinal axis. According to my invention the strength and resistance of such cross member construction is improved by adding structural members extending out of the ring's plane, thereby 15 developing the cross member to a spatial truss. With increased size and diameter of the ship, and with increased gas pressure, this ring construction will be of great advantage. The possible occurrence of 20 plus pressure on one side of a cross member will be much better resisted and the danger of distortion will be lessened.

Furthermore, a ring construction embodying my invention permits of loads to be distributed on the lower parts thereof, especially when the rings form corridors extending at right angles from the longitudinal corridor usual with rigid airships. The provision of a number of such cross corridors 25 facilitates the supervision of the hull structure and especially that of the walls of the gas cells during the flights, which is of highest importance.

For the purpose of increasing the advantage 30 with such cross corridors it may be useful to provide not only the usual longitudinal corridor at the lowest part of the ship, but to add other longitudinal corridors at any place of the ship's circumference, 35 which now will be easily accessible by means of the new cross corridors according to my invention. For example, a longitudinal corridor at the ridge of the ship will permit supervision of the operated valves during 40 flight, which is an advantage of greatest value.

Having described my invention in a general way, I now want to point out the details thereof referring to the annexed drawing 45 showing examples embodying my invention.

Fig. 1 is a cross section through a rigid airship showing a ring member.

Fig. 2 is a vertical section through the middle of Fig. 1 looking to the left. 55

Figs. 3 and 4 correspond to Figs. 1 and 2 respectively but show another example of ring construction according to my invention.

Figs. 5 and 6 illustrate another example 60 in side view and cross section respectively, while Figs. 7 and 8 show cross sections of other modifications of ring structures.

In Fig. 1 the longitudinal girders are designated by letters a^1 to a^{12} . The sides 65 of the polygon are formed by the ring girders b . The corners of the rings are numbered 1 to 12. Girders c are provided connecting oppositely situated ring corners, for example, corner 1 to corner 6, 12 to 7, 3 70 to 10 and 4 to 9. These girders c are not situated in the plane of the ring but they project out of that plane and are provided in pairs, creating points of intersection 13, 13', 14, 14', 15, 15' and 16, 16'. These points 75 are situated symmetrically with regard to the original ring plane, as may be seen from Fig. 2. Posts p may be provided connecting 13 to 13', 14 to 14', 15 to 15' and 16 to 16', and it is useful to brace the points 80 of intersection and the ring corners by wires d . Thus the whole cross member constitutes a substantially ring shaped truss of lentil-like cross section.

Instead of spacing apart the middle part 85 of a formerly plane ring structure, as done in Figs. 1 and 2, you may as well space apart the outer annular part, which means duplicating the ring girders and providing an inside structure to connect them together. 90 This connection is made by a ring shaped truss of triangular cross section forming a corridor, as may be seen from Fig. 5, in which e^1 and e^2 designate the girders of the two outer rings and g the additional girders for constituting the ring truss. The inner corners of this ring truss are braced by wires h , shown in Fig. 6. In this figure a longitudinal corridor i on the top of the ship is marked.

Figs. 7 and 8 show variations of this construction. In Fig. 7 two longitudinal corridors i' and i'' are provided and ladders k are shown making the upper part of the ring truss accessible. Fig. 8 gives three longitudinal corridors i , i' and i'' . Here

the shape of the ship is flattened at its lower part between the corridors i' and i^2 , which may be useful under certain conditions.

- In Figs. 3 and 4 not only the middle part 5 of the ring, as in Figs. 1 and 2, or its outer parts, as in Figs. 5 to 8, are spaced apart, but the whole ring structure is duplicated and the two rings situated at a comparatively short distance apart are each provided 10 with intersecting girders e and braced by wires d . The points of intersection of these girders 13 and 13', 14 and 14', 15 and 15', 16 and 16' are connected by posts h , and the structure is braced by wires f .
- 15 It is to be understood that I do not limit myself to the exact details described or shown in the drawing as many variations will occur to persons skilled in the art.

What I claim is:

- 20 1. A rigid airship comprising a longitudinal member and a cross member, said cross member comprising a plurality of girders, part of said girders being so arranged in one common plane substantially at right angles 25 to the longitudinal axis of said airship as to form a substantially polygonal truss with rigid circumferential members, another part of said girders being situated out of the plane of said polygonal truss and being arranged in pairs substantially symmetrically 30 thereto.

- 25 2. A rigid airship comprising a longitudinal member and a cross member; said cross member comprising a plurality of girders, part of said girders being so arranged in one common plane substantially at right angles to the ship's longitudinal axis as to form a substantially polygonal truss with rigid circumferential members, another part of said 35 girders being so arranged as to form two other substantially polygonal trusses with rigid circumferential girders, said two other polygonal trusses being arranged substantially symmetrically to said first truss and its 40 plane.

- 45 3. A rigid airship comprising a longitudinal member and a cross member; said cross member comprising a plurality of girders, part of said girders being so arranged in one common plane substantially at right angles 50 to the ship's longitudinal axis as to form a substantially polygonal truss with rigid circumferential members, another part of said girders being so arranged as to form two 55 other substantially polygonal trusses with rigid circumferential girders, said two other polygonal trusses being arranged substantially symmetrically to said first truss and their diameters being substantially equal but 60 substantially larger than the diameter of said first truss.

4. A rigid airship comprising a longitudinal member and a cross member; said cross

member comprising a plurality of girders, part of said girders being so arranged in one 65 common plane substantially at right angles to the ship's longitudinal axis as to form a substantially polygonal truss with rigid circumferential members, another part of said girders being so arranged as to form two 70 other substantially polygonal trusses with rigid circumferential girders, said two other polygonal trusses being arranged substantially symmetrically to said first truss and their diameters being substantially equal but 75 substantially larger than the diameter of said first truss; a third part of said girders being so arranged as to connect said first polygonal truss with said other two polygonal trusses.

5. A rigid airship comprising a longitudinal member and a cross member; said cross member comprising a plurality of substantially polygonal trusses each arranged in a different plane and made up of rigid circumferential girders, and girders connecting said trusses with each other; said truss forming girders and said connecting girders being so arranged in relation to each other that the structure of said cross member made up of all said girders is substantially symmetrical to a plane drawn at right angles to the ship's longitudinal axis.

6. A rigid airship comprising a plurality of longitudinal members and a cross member; said cross member comprising three polygonal trusses with rigid circumferential girders, one of said trusses being of substantially smaller diameter than the diameters of the other two trusses, and girders connecting said smaller truss with said other two trusses; said longitudinal members being connected to the corners of said two other larger trusses.

7. A rigid airship comprising members extending longitudinally thereof, said members including a longitudinally extending corridor disposed at each side of the airship below the medial horizontal plane bisecting the airship, and a transversely disposed truss construction forming a gangway extending circumferentially of the lower portion of the airship and intersecting each longitudinal corridor.

8. A rigid airship comprising members extending longitudinally thereof, said members including a longitudinally extending corridor disposed at each side of the airship below the medial horizontal plane bisecting the airship, and a transversely disposed polygonal truss construction forming a gangway extending circumferentially from top to bottom of the airship and intersecting each longitudinal corridor.

In testimony whereof I affix my signature.

KARL ARNSTEIN.
